Will D. Candee,
INVENTOR

BY J. W. Shueley

ATTORNEY

UNITED STATES PATENT OFFICE.

WILL D. CANDEE, OF LOS ANGELES, CALIFORNIA, ASSIGNOR OF ONE-HALF TO ANNA K. SMITH, OF SPRINGVILLE, NEW YORK.

GOVERNOR.

Application filed February 23, 1926, Serial No. 90,225. Renewed July 28, 1928.

This invention relates to speed governors for internal combustion engines, and has for its principal object the provision of a governor adapted for use in connection with 5 automotive engines which are converted to stationary uses.

Another object of the invention is to provide a duly sensitive governor which is simple in design and readily adjusted to any 10 of a wide range of speeds.

Another object of the invention is to provide a governor which is well protected against dust, moisture and moving objects.

Still other objects of the invention is to 15 provide a stock form of governor which any one at all skilled in the use of internal combustion engines may install and adjust with the most simple tools.

Further objects of the invention include 20 the provision of safety means to take effect in case the governor should break, and the provision of means whereby the purchaser of a stock governor may readily adjust the said safety means in conformance 25 with the angles at which the governor bolt drives the governor pulley.

Still other objects and advantages will appear hereinafter and will be better understood by virtue of the order of their occurrence. 30

I have illustrated by the accompanying drawings a preferred embodiment of my invention, it being understood that this embodiment which is hereinafter described in 35 detail, is by way of example, only, inasmuch as there are numerous other embodiments which, while differing in construction and arrangements of parts, are within the scope of my invention.

40 In the said drawings,

Figure 1, is a view in front elevation of the said embodiment.

Figure 2, is a view in rear elevation thereof, showing the governor weight disposed 45 in the outermost position which it assumes when acted upon by centrifugal force.

Figure 3, is a view mainly in vertical section thereof as seen on a line 3-3 of Fig. 1, showing the governor weight in the position 50 which it assumes when the governor is idle.

Figure 4, is a view in front elevation of a part of the device known as the cam member.

More specifically, my improved governor 55 includes, among other parts, a bracket 6, a combined pulley and housing 7, and a governor push rod 17. The embodiment illustrated is adapted to be driven by a belt, such as 9, running over the pulley 8, and, as will 60 be apparent from the following description, rotation of the pulley at an excess speed will result in the push rod being thrust out into dotted line position. The bracket which is provided with a drilled hole 10, may be 65 attached to any suitable part of almost any type of internal combustion engine (not shown); the push rod being operatively connected to the throttle or carburetor thereof, while the belt runs over the fly wheel of said 70 engine or over other suitable driving element. The various expedients employed for attaching a governor to an engine for which it was not especially designed are 75 well known and need no further description.

The bracket is provided with a horizontal boss 11, which is bored, as at 12, to receive a hollow tubular axle 14, fixed thereto against rotation by a set screw 15. A hole 80 16 is drilled in the bracket coaxial with the bore 12, and through this hole an end 17 of the push rod extends. The other end 18 of the said push rod is enlarged and is 85 slidable in a bore 19 of the tubular axle. A light spring 20 holds the push rod yieldably in the position shown.

A safety device to take effect in event of the belt breaking is provided in the form of a cam member 21, and a belt idler 22. 90 The cam member is trunnioned on the bracket by a cap screw 23, and is provided with a substantially U-shaped recess 23' which is disposed about the push rod in such a manner that oscillation of the cam member to either side will cause the corresponding margin to engage the push rod and hold it locked in the exact position which it is in at the time of the breaking of the belt. The cam member is actuated by the weight of the 100 idler which is mounted to revolve on the bent end 24 of an arm 25. The idler is adjustably held in a boss 26 by a set screw 27.

When the device is sold to a customer, the cam member is disposed in the position 105 shown in Fig. 4; there being a second and lower hole 28 in which the screw may be disposed. The purchaser is instructed to

install the governor on his engine so that the exact angle at which the arm 26 will be inclined, is definitely known. That portion of the cam member coming immediately below the push rod is marked and the cam member is removed from the governor until the recess or notch is ground out at the point indicated. The cam member is then reinstalled in the position shown in Fig. 3.

10 The combined pulley and housing is of cup form and partially encloses a space 30. The annular wall 31 of the housing provides the pulley surface, while a web at the outer end connects said pulley with an internal coaxial and integral sleeve 33. Said sleeve is a running fit over the tubular axle; an enlarged end 34 on the latter coacting with the boss on the bracket to hold the pulley operatively fixed thereon. Within 15 the cup-like housing diametrically opposed bosses 35 are provided; said bosses being located toward the open end of the housing. In each boss there is fixed a short protruding gudgeon pin 36, each extending toward 20 the other into the said space, but terminating just short of the sleeve 33, to avoid interferences. Jointly on said pins there is trunnioned a governor weight 37. Said governor weight may be best characterized 25 by saying that it is of interrupted ring-form; it being divided to leave a space 37', so that it may move into broken line position, (Fig. 3), without interfering with the sleeve and axle. The uninterrupted half of 30 the weight as indicated at 38 is substantially round in cross section, while the terminations 38' are flattened and broadened into substantially disc form. In other words, 35 the respective portions of the weight which lie to either side of its center of oscillation are so proportioned as to weigh substantially the same so that the weight is balanced 40 on the gudgeon pins.

It is a well known fact that a ring which 45 is trunnioned as shown, and inclined at an angle, will, upon the housing being rotated, forcibly assume an upright position as indicated by the broken lines in Fig. 3.

A rod 39 is slidably fitted in the open end 50 of the tubular axle to abut the enlarged end of the push rod. Rod 39 and push rod 17 may be collectively termed a divided push rod; it being understood that the safety device may act to hold push rod 17 against 55 retractile movement while rod 39 is independently operated by the governor weight. The last named rod is operatively connected to the governor weight, and this may be done in various ways, but in the embodiment 60 shown, I provide a wire yoke 40 for this purpose. Said yoke is fixed at one end 40' of the rod and extends vertically to a right angle bend 41. From the bend it extends parallel to the annular wall of the housing 65 an appreciable distance. Recesses, such as

42, are provided in light webs 43, which are integral with the annular wall of the housing, act to guide the yoke in its movements. It should be noted that these webs in guiding the yoke cause the rod and the 70 yoke to revolve with the housing, while the push rod 17 tends not to rotate. The yoke is bent back upon itself at 44, and is bent again at 45 to return to the rod 39.

Referring particularly to Fig. 2, it will be 75 seen that each gudgeon pin is locked in its boss by a set screw 46. Loosening of this set screw permits of the pin being revolved in its boss. To resist the tendency of the governor weight to assume vertical position, 80 a governor spring 47 is provided. Said spring is turned several times about one of the gudgeon pins. One end 48 of the spring is looped around a cotter pin 49 carried by said gudgeon pin, while the other end 50 85 of the spring is hooked over a screw 51 carried by the enlarged end of the weight. A screw driver slot 52 is provided in the gudgeon pin. To adjust the tension of the spring for a given speed, the set screw is 90 loosened and the gudgeon pin is turned as required to increase the tension of the spring. When this is done, tightening of the set screw locks the adjustment.

From the foregoing description of my improved governor, it will be apparent that 95 rapid rotation of the housing will result in the governor weight tending to assume vertical position against the resistance of the governor spring. Just as the governor 100 weight starts to raise, pressure on the round portion of the weight on the rod 39 is relieved, and as its weight continues to change position, the rod is easily moved inward through the medium of the yoke. As a 105 result, the push rod advances. In all other respects my improved governor functions like the majority of sensitive governors, in that even slight excess of speed results in a very marked movement of the push rod. 110 Lubrication of the entire device is effected through a small oil hole 55; the oil spreading between the sleeve and axle and being retained in a basin 56, milled out of the said axle.

115 It will be apparent now that I have provided a simple governor capable of carrying out the above objects and in which all parts are well housed and lubricated, and in which the effective range of the push rod is relatively great for the other dimensions of the governor, and while I have shown a specific construction and arrangement of parts, I do not limit myself to any specific construction or arrangement of parts and may alter 120 same without departing from the spirit of the invention, within the appended claims.

I claim:

1. In a governor, a revoluble hollow cylindrical housing, an axle for said housing, a 125

coaxial internal sleeve to said housing revoluble on said axle, an annularly disposed weight in the interior of said housing journaled therein to oscillate on an axis which 5 extends diametrically across said housing at right angle to the axis of rotation of said housing whereby said weight tends to dispose itself, upon rotation of the housing, in parallel relation to the perimeter of the 10 housing, and yieldable means normally tending to hold said weight inclined at an angle to the aforesaid position; said annular weight being broken away at one point to avoid interference with said sleeve and the 15 divided ends of said weight where it is broken away being enlarged to provide for balance.

2. In a governor, a bracket arm, a hollow boss at one end thereof, a hollow axle fixed 20 in said hollow boss, an annular enlargement to that end of said axle which is opposed to the end fixed in the boss, a sleeve revoluble on said axle disposed intermediate of said boss and enlargement, a divided push rod 25 extending through said axle; one end of said divided push rod extending through said boss and bracket and the other end of said push rod extending from the other end of said sleeve, a pulley rim carried by 30 said sleeve, and a governor weight in the space encompassed by said rim and journaled in said rim on an axis diametrically disposed with regard thereto; said weight being operable upon said push rod.

3. A governor as in claim 2 and further including; a cam element journaled to said bracket and disposed to frictionally engage the push rod where it protrudes through the bracket, an arm extended from said cam

member, and a belt idler carried on the said 40 arm.

4. In a governor, a stationary sleeve, a 45 push rod movable longitudinally in said sleeve, a centrifugally operable means revoluble on said sleeve operable to so move said push rod, a bracket arm extending radially from said sleeve, a cam member pivoted on said bracket arm adjacent said push rod and movable to frictionally engage same, and a belt idler fixed to said cam member to 50 move said cam by gravity into frictional engagement with said push rod.

5. As an article of manufacture, a governor comprising a centrifugal mechanism, a 55 push rod longitudinally movable by same, a fixed member through which said rod protrudes, a cam, and a pivot for said cam carried by said fixed member adjacent said rod; said cam member having a semi-circular cam surface coaxial to the pivot center of said pivot; said pivot being adjustable along said fixed member in a path radial to the longitudinal axis of said rod.

6. As an article of manufacture, a governor comprising a centrifugal mechanism, a 60 push rod longitudinally movable by same, a fixed member through which said rod protrudes, a cam, and a pivot for said cam carried by said fixed member adjacent said rod; said cam member having a semi-circular cam surface coaxial to the pivot center of said pivot; said pivot being adjustable along 65 said fixed member in a path radial to the longitudinal axis of said rod, and said cam being adapted for machining to alter the 70 said semi-circular surface of said cam.

WILL D. CANDEE.
